COMBINED LAMP AND PLANTER

Jack F. Clark and Lloyd F. Ellis,
South Whittier, Calif.

Application July 19, 1952, Serial No. 20,692

Term of patent 3½ years

(Cl. D43—23)

To all whom it may concern:

Be it known that we, Jack F. Clark and Lloyd F. Ellis, citizens of the United States, residing in South Whittier, in the county of Los Angeles and State of California, have invented a new, original, and ornamental Design for a Combined Lamp and Planter, of which the following is a specification, reference being had to the accompanying drawing, forming part thereof.

Fig. 1 is a side elevational view of a combined lamp and planter, showing our new design.

Fig. 2 is a bottom plan view thereof.

Fig. 3 is a top plan view shown to a reduced scale.

The dominant features of the design are shown in full lines.

We claim:

The ornamental design for a combined lamp and planter, substantially as shown and described.

JACK F. CLARK.
LLOYD F. ELLIS.
